UNITED STATES PATENT OFFICE.

CARL H. EPPLER, OF OAKLAND, CALIFORNIA.

CHECK-PROTECTOR.

1,163,988.

Specification of Letters Patent. Patented Dec. 14, 1915.

Application filed March 16, 1915. Serial No. 14,731.

To all whom it may concern:

Be it known that I, CARL H. EPPLER, a citizen of the United States, residing at Oakland, in the county of Alameda and State of California, have invented certain new and useful Improvements in Check-Protectors, of which the following is a specification.

This invention relates to improvements in check protectors and has for its principal object the construction of a small device of this character which may be carried on or about the person of a user.

Another object of my invention is to so construct the device that the check is effectively protected against alterations, and, still a further object is to provide a device which is neat and simple, and may be sold at a nominal price.

With these and other objects in view my invention consists in the novel construction, combination and arrangement of parts as set forth in the following specification and more particularly pointed out in the appended claims.

Reference being had to the accompanying drawing forming a part of this specification, Figure 1 is a view in perspective showing the manner in which my improved device is used to protect checks. Fig. 2 is a view in side elevation of the interior portions of the protector, the casing being in section. Fig. 3 is a view in section taken at right angles to the view in Fig. 3. Fig. 4 is a view in side elevation of a modified form of roller used with my device. Fig. 5 is a view in side elevation of the device with the lid in position on the case.

Referring to corresponding parts by the same numerals of reference, 1 denotes the outer case provided with a lid 2. This case is rectangular in horizontal cross section and within the case is a U-shaped spring form 3 having pivotally mounted adjacent the outer ends of the U a roller 4, consisting of a series of circumferentially disposed cutting edges 6. While I prefer to construct this roller with continuous cutting edges I may find it advantageous to use the circumferentially disposed cutting points 5 as shown in Fig. 4.

Pivots mounted in the frame 2 above the roller 4 is a cylindrical inking pad of absorbent material moistened with a special ink, which under the influence of any of the chemical solutions used for erasing the ordinary writing fluid, has a tendency to spread through the fiber of the paper, thereby imparting a stain which indicates to an observer that a check has been tampered with. The U-shaped form has substantially the outline of the container case 1, and is adapted to fit snugly within the same and to be held therein by frictional contact.

The device is used by removing the cap 2 and after the check is written running the roller longitudinally along the words denoting the amount for which the check is drawn, thus leaving a number of rows of lines partly cut into the paper, or rows of short dots, in which is deposited the ink from the pad. This ink is not only deposited on the surface but into the fabric of the paper. Whenever an attempt is made to erase the figures indicating the amount of the check, this ink will spread and run indicating at once that the check has been changed. A further protection is also afforded due to the fact that a word can not be written over the perforated cut lines without the ink running into these cut portions, thus showing a ragged line rather than a smooth one when the same is written over an unbroken surface.

While I have shown the preferred embodiment of my invention it will be understood that changes may be made in detail and design without departing from the scope of the claims.

What I claim as new and wish to cover by Letters Patent is:—

1. A check protector comprising a casing, a U-shaped spring frame frictionally held in said casing, a roller pivotally mounted in said spring frame, a plurality of circumferentially disposed cutting edges carried by said roller and means for inking said cutting edges.

2. A check protector comprising a casing, a U-shaped spring frame frictionally held in said casing, a roller pivotally mounted in

said frame and having one edge extending outside of said casing, and means for inking said roller.

3. A check protector comprising a casing,
5 a U-shaped spring frame frictionally held in said casing, a roller pivotally mounted in said frame and having one edge extending outside of said casing, a plurality of circumferentially disposed cutting edges carried by

said roller, and an absorbent roller pivotally mounted adjacent said cutting roller and adapted to convey ink thereto.

In testimony whereof I affix my signature in presence of two witnesses.

CARL H. EPPLER.
